UNITED STATES PATENT OFFICE

126,857

DESIGN FOR A PLASTIC BUILDING OR PAVING BLOCK

Charles H. Rothmann, Closter, N. J.

Application December 29, 1939, Serial No. 89,208

Term of patent 14 years

To all whom it may concern:

Be it known that I, Charles H. Rothmann, a citizen of the United States, residing in Closter, in the county of Bergen and State of New Jersey, have invented a new, original, and ornamental Design for a Plastic Building or Paving Block, of which the following is a specification, reference being had to the accompanying drawing, forming part thereof, in which:

Figure 1 is a perspective view of the plastic

building or paving block, showing my new design;

Figure 2 is an end elevation of the same; and Figure 3 is a side elevational view of the block looking from the opposite side from that shown in Figure 1.

I claim:

The ornamental design for a plastic building or paving block, as shown.

CHARLES H. ROTHMANN.
